F. RUBY.

AUTOMATIC RAILROAD ACCIDENT PREVENTER.

APPLICATION FILED DEC. 15, 1921.

1,414,376.

Patented May 2, 1922.

UNITED STATES PATENT OFFICE.

FRANK RUBY, OF BRIDGEPORT, CONNECTICUT.

AUTOMATIC RAILROAD-ACCIDENT PREVENTER.

1,414,376.

Specification of Letters Patent.

Patented May 2, 1922.

Application filed December 15, 1921. Serial No. 522,523.

To all whom it may concern:

Be it known that I, FRANK RUBY, citizen of Hungary, residing at Bridgeport, in the county of Fairfield and State of Connecticut, have invented certain new and useful Improvements in Automatic Railroad-Accident Preventers, of which the following is a specification.

This invention relates to a block signal system for railroads adapted to give notice to any train if there is a train immediately ahead.

The invention has for an object to provide a novel and simple type of block signal system.

For further comprehension of the invention, and of the objects and advantages thereof, reference will be had to the following description and accompanying drawings, and to the appended claims in which the various novel features of the invention are more particularly set forth.

Fig. 1 of the drawings is an elevational view showing a portion of a track, with the contact elements adapted for operation by a passing train, indicating the latter in normal position, with the block clear.

Fig. 2 is a transverse vertical section on the line 3—3 of Fig. 1.

Fig. 3 is a similar view, but indicating the contact elements in position assumed when the block is occupied.

Fig. 4 is a detail face elevation of the signal element.

Fig. 5 is a side view thereof.

Fig. 6 is a diagram of the wiring connections.

Referring now to the drawings I have indicated a portion of a track rail at 10, supporting ties being indicated at 11. As part of my improved system each train is provided with a depending element adapted to operate certain electrical contacts, and this depending element is preferably constructed by providing a wheel 12 with a flange 13 of greater depth than the ordinary wheel flanges. Any desired wheel on the locomotive or other part of the train may be employed for this purpose.

At the entrance to each block I provide a depressible member consisting of a lever arm 15 which is fixed on a transverse rock-shaft 16 which extends into a switch box 17 located beside the track. Fixed to the shaft 16 within the box 17 are a pair of arms 18 and 19 arranged at a slight angle

to one another and having respectively a roller 20 and a weight 21 on their free ends. The parts are so arranged that the counter-weight 21 holds the lever 15 inclined slightly upwardly toward its free end so as to be engaged by the flange of wheel 12.

Suspended freely from a bracket 23 in the box 17 is an arm 24 having bridge pieces 25 and a hook 26 mounted upon opposite sides of its free end and insulated therefrom. This arm 24 is located in front of the arm 18 so as to be engaged by the roller 20 and swung upwardly when lever 15 is depressed. Fixed to the free end of this arm 24 is a solenoid plunger element 28 with which is concentrically alined (with respect to the pivot point of arm 24) a solenoid 29 suitably supported in the box 17. Mounted on one end of the solenoid 29 are a pair 75 of comparatively stiff spring contact fingers 30 adapted to be engaged by the bridge piece 25 when lever 15 is operated by the flanged wheel 12. As shown in the drawings the roller 20 bears on arm 24 comparatively near 80 the pivot end thereof to cause a slight movement of lever 15 to impart a larger movement to the arm 24. Within the box 17 a pair of spring contact fingers 32 and 33 are mounted the contact finger 32 being longer 85 than the finger 33 and adapted to be engaged by the hook 26 when the arm 24 swings, these contacts 32, 33 forming part of the circuit of the adjacent block to that of which the contact studs 30 form part.

The signal element which I preferably use comprises an electric lamp 35 mounted in a circular housing 36 provided on opposite sides with a red lens 37 and a green lens 38. The housing is mounted on a suitable post or tower, the upper portion of which is indicated at 40, the housing being arranged to turn through an angle of ninety degrees. To this end of the housing is fixed a hollow vertical shaft 41 suitably journaled in horizontal elements 40' at the top of the tower. This shaft has fixed thereto an armature 42 located between a pair of fixed pole pieces 43 provided with suitable windings. When current flows through these 105 windings the armature is drawn to a position with the red lens 37 facing rearwardly. The housing 36 is normally held at right angles to the above mentioned position by means of a coiled spring 43 surrounding the shaft 41 and connected at one end thereto and at its other end to one of the tower 110

members 40'. Current to the lamp 35 is supplied from separate leads, the circuit to the lamp being closed only when the pole pieces 43 are energized. To this end a cam 5 45 is fixed to the lower end of the shaft 41 and is adapted to bear on a spring contact 46 and move it into engagement with a fixed contact 47, these contacts being included in the lamp circuit and being suitably mounted 10 ed on the tower 40.

In the wiring connections one end of the solenoid coil 29' is connected to one of the fixed contacts adapted to be bridged by bar 25 when lever 15 is operated. From the opposite end of the solenoid coil a wire 50 leads to the windings 43' of the pole pieces 43 and from these windings a wire leads to the contact 32. From the contact 33 a wire 53 leads to battery 54 and from battery a 20 wire 55 leads to the other contact 30. As will be understood the contacts 32, 33 of each block form part of the circuit of the preceding block. Current is supplied to the lamps 35 through two leads 56 and 57 25 from which branches 58 and 59 lead to the lamp, the switch contacts 46, 47 being placed in one of these branches.

The operation of my improved block signal system is as follows: When lever 15 is 30 engaged by the flange of wheel 12, the arm 24 is swung to cause contacts 30 to be bridged by the bar 25, the circuit being closed through the coils of the pole pieces 43 which cause the armature 42 to swing through 35 ninety degrees, correspondingly swinging the housing 36 and facing the red lens toward the rear. At the same time the solenoid 29 is energized and by its attraction on the plunger 28 holds the bar 25 in engagement 40 with the contacts 30, keeping the lamps illuminated, and the red lens facing rearwardly until the lever 15 at the entrance to the next block is depressed, the hook 26 pulling back the contact 32 and breaking 45 the circuit. The arm 24 then falls backward, opening the circuit at the contacts 30 while the spring 43 rotates the shaft 41 back to normal position, opening the lamp circuit. The shaft 45 may be held in normal position 50 by a lug 65 on the shaft engaging a lug 66 on the tower frame. The wires to the lamp 35 may be conveniently led up through the hollow shaft 45.

Having thus described my invention what 55 I claim as new and desire to protect by Letters Patent of the United States is as follows:

1. In a block signal system, an inclined lever adapted to be mounted adjacent a 60 track rail and be depressed by a passing train, a pivoted arm adapted to be swung by said lever, a solenoid, a solenoid plunger carried by said arm, an electric signal operating element having said solenoid included in its circuit, and a pair of contacts

included in said circuit adapted to be bridged by the said arm.

2. In a block signal system, an inclined lever adapted to be mounted adjacent a track rail and be depressed by a passing train, a 70 pivoted arm adapted to be swung by said lever, a solenoid, a solenoid plunger carried by said arm, an electric signal operating element having said solenoid included in its circuit, and a pair of contacts included in 75 said circuit adapted to be bridged by the said arm, said contacts comprising spring fingers mounted adjacent the end of said solenoid in which the said plunger engages.

3. In a block signal system, an inclined 80 lever adapted to be mounted adjacent a track rail and be depressed by a passing train, a pivoted arm adapted to be swung by said lever, a solenoid, a solenoid plunger carried by said arm, an electric signal operating 85 element having said solenoid included in its circuit, and a pair of contacts included in said circuit adapted to be bridged by the said arm, said contacts comprising spring fingers mounted adjacent the end of said solenoid 90 in which the said plunger engages, said bridging element comprising a bar fixed on said arm.

4. In a block signal system, an inclined lever arranged adjacent a track rail, a 95 weighted arm rigid with said lever, a second arm adapted to be engaged by the first arm, a solenoid, a plunger for said solenoid fixed on the second arm, a pair of spring contacts arranged adjacent one end of said solenoid, 100 a bridge piece carried by said arm and adapted to engage said contacts, an electric signal operating element having said solenoid and contacts included in series in its circuit, and means for automatically closing 105 the circuit through the electric signal when the said operating element is energized.

5. In a block signal system, an inclined lever arranged adjacent a track rail, a weighted arm rigid with said lever, a second 110 arm adapted to be engaged by the first arm, a solenoid, a plunger for said solenoid fixed on the second arm, a pair of spring contacts arranged adjacent one end of said solenoid, 115 a bridge piece carried by said arm and adapted to engage said contacts, an electric signal operating element having said solenoid and contacts included in series in its circuit, and means for automatically closing the circuit through the electric signal when the said operating element is energized, said means including a shaft, a cam carried by said shaft, and a contact member adapted to be engaged by said cam.

6. In a block signal system, an inclined 125 lever adapted to be mounted adjacent a track rail and be depressed by a passing train, a pivoted arm adapted to be swung by said lever, a solenoid, a solenoid plunger carried by said arm, an electric signal operat- 130

ing element having said solenoid included in its circuit, and a pair of contacts included in said circuit adapted to be bridged by the said arm, said contacts comprising spring fingers mounted adjacent the end of said solenoid in which the said plunger engages, said bridging element comprising a bar fixed on said arm, and a hook fixed on said arm and adapted to engage and separate a pair 10 of contacts forming part of the circuit of the preceding block.

7. In a block signal system, an inclined lever adapted to be mounted adjacent a track

rail and be depressed by a passing train, a pivoted arm adapted to be swung by said lever, a solenoid, a solenoid plunger carried by said arm, an electric signal operating element having said solenoid included in its circuit, and a pair of contacts included in said circuit adapted to be bridged by the 20 said arm, and a flanged wheel on the train adapted to engage and depress said lever.

In testimony whereof I have affixed my signature.

FRANK RUBY.
